UNITED STATES PATENT OFFICE

152,148

DESIGN FOR A CABINET FOR LUBRICATING EQUIPMENT

Richard P. Field, Cincinnati, Ohio, assignor to Balcrank, Inc., Disney, near Marburg, Cincinnati, Ohio, a corporation of Ohio

Application January 14, 1947, Serial No. 136,143

Term of patent 7 years

(Cl. D52—2)

To all whom it may concern:

Be it known that I, Richard P. Field, a citizen of the United States, residing at Cincinnati, in the county of Hamilton and State of Ohio, have invented a new, original, and ornamental Design for a Cabinet for Lubricating Equipment, of which the following is a specification, reference being had to the accompanying drawings, forming a part thereof.

Figure 1 is a perspective view of a cabinet for lubricating equipment, showing my new design.

Figure 2 is a front view thereof.

Figure 3 is a side view thereof.

Figure 4 is a top view thereof.

The dominant features of my design reside in the portion shown in full lines.

I claim:

The ornamental design for a cabinet for lubricating equipment, substantially as shown and described.

RICHARD P. FIELD.
